CLAIM

The ornamental design for a plate for denture creation, as shown and described.

DESCRIPTION

FIG. 1 is a front view of a plate for denture creation showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a cross-sectional view thereof, taken along line 7-7 in FIG. 5;

FIG. 8 is a top perspective view thereof; and,

FIG. 9 is a bottom perspective view thereof.

The plate for denture creation shown in FIGS. 1-9 is entirely transparent.

The dot-dash broken lines shown in FIG. 5 are included to represent the indication of the cross-sectional view and form no part of the claimed design.
